United States Patent Office

Des. 176,171
Patented Nov. 29, 1955

176,171

FIGURINE

Ruth A. Barone and Joseph Swbado, Toledo, Ohio

Application February 2, 1955, Serial No. 34,328

Term of patent 7 years

(Cl. D29—23)

FIG. 1

FIG. 2

Figure 1 is a front perspective view of the figurine, showing our new design; and

Figure 2 is a rear perspective view of the figurine.

We claim:

The ornamental design for a figurine, as shown.

References Cited in the file of this patent

Trophy Headquarters, page 48, Item No. 5167, January 1942.